JOHN B. LOWELL, OF BALTIMORE, MARYLAND.

Letters Patent No. 72,650, dated December 24, 1867.

IMPROVEMENT IN STEAM-ENGINE GLOBE-VALVES.

The Schedule referred to in these Letters Patent and making part of the same.

TO ALL WHOM IT MAY CONCERN:

Be it known that I, JOHN BURNETT LOWELL, of Baltimore, in the county of Baltimore, and State of Maryland, have invented a new and improved Globe-Valve; and I do hereby declare the following to be a full, clear, and exact description of the same, reference being had to the accompanying drawings, forming part of this specification, and in which—

Figure 1 is a longitudinal section of a globe-valve, showing a vertical section of my invention in connection therewith.

Figure 2 is a vertical cross-section through the same.

Figure 3 is a top view of the valve, with the hand-wheel removed.

Figure 4 is a perspective view of the hand-wheel upside down.

Similar letters of reference indicate corresponding parts in the several figures.

In this invention a new device is employed for grinding the valve to its seat without removing the valve.

In the drawings, A represents a pipe expanded into a globular chamber at A', in which is provided a stout partition, a, separating the globular chamber into two compartments, one communicating with one end of the pipe A, and the other with the other end. The partition is constructed in the form shown in fig. 1, in order to afford a valve-seat, a', which shall accommodate a valve working at right angles with the main pipe A. This valve is an ordinary circular plug-valve, shown at e, seating downward upon the valve-seat a'. The valve C extends through the walls of the chamber A', and works in a sleeve, e, which screws up and down through the wall of the chamber, by means of the threads i i i. When the sleeve is screwed down, it presses upon the valve e, and seats it. When unscrewed, it releases the valve, which will then open by any pressure from beneath. That part of the valve-stem enclosed within the sleeve is cylindrical in form. Above the sleeve, from the point x to the point x', or the top of the stem, it is square or polygonal. Both the sleeve and the valve-stem are worked by means of a hand-wheel, w, which is provided on one side with a central clutch, v, that operates upon the sleeve when the wheel is placed with that side down, as shown in fig. 1, turning the sleeve in either direction, and screwing it down or up as the case may be. When the sides of the wheel are reversed, as shown in fig. 2, the clutch projecting upward and the flat side of the wheel downward, the wheel does not operate upon the sleeve at all, but only on the valve-stem, which being square or polygonal at that point, enters a square or polygonal aperture or socket, provided at the centre of the wheel for the purpose, and is held there firmly, and turned in either direction with the wheel. The square or polygonal socket does not extend entirely through the wheel, but only on one side of it, so that the wheel operates as a wrench upon the valve-stem only when placed with that side down. When placed with that side up, the square part of the valve-stem does not quite reach up to the square socket of the wheel, and it accordingly leaves the valve-stem free while the force of the wheel is exerted upon the sleeve e by means of the clutch.

By this arrangement the hand-wheel can be used for seating or opening the valve, or, by simply turning it upside down, it may be used for turning the valve alone, with any required degree of force, for the purpose of grinding the valve to its seat. This may be done, it is evident, without removing the valve or interfering with the parts in any way, except simply to reverse the position of the hand-wheel.

As the valve will need grinding only once in a great while, the ordinary position of the several parts of the device will be that shown in fig. 1. When in this position, the aperture through the centre of the hand-wheel may be closed, and the wheel confined in its place by means of a button, b, fixed to a screw-stem, which passes through the aperture and screws into the top of the valve-stem, as shown at o. D is an opening, through which emery may be introduced to assist in grinding the valve. E is another opening, through which light can be admitted to the valve-seat during the grinding, and the progress of the work be inspected. Both openings may be closed by a screw-plug at all other times.

Having thus described my invention, what I claim as new, and desire to secure by Letters Patent, is—

The combination of the hand-wheel, constructed with the clutch v and the square opening, as described, with the sleeve e and valve-stem C, the latter being constructed as set forth, and all the parts operating together, substantially in the manner and for the purpose specified.

JOHN B. LOWELL.
